[57] CLAIM

The ornamental design brace for bowling pin setter deck, as shown and described.

DESCRIPTION

FIG. 1 is a perspective view of a brace for bowling pin setter deck showing my new design;

FIG. 2 is a front elevational view thereof; the rear elevational view being a mirror image thereof;

FIG. 3 is a top plan view thereof;

FIG. 4 is a bottom plan view thereof; and,

FIG. 5 is a left side elevational view thereof; the right side elevational view being a mirror image thereof.

The broken line showing of a deck is for illustrative purposes only and forms no part of the claimed.
